METHOD FOR TREATING TEXTILE GOODS
OF ANY DESCRIPTION

Walter Rotta, Zwickau, Germany

No Drawing. Application September 21, 1933,
Serial No. 690,501. In Germany September 23,
1932

3 Claims. (Cl. 91—68)

The British specification No. 251,993 has disclosed how solutions containing urea can result in dressing effects on fibrous matter. It is described there that by the treatment done with urea a smooth and moist feel may be imparted to the fibrous matter, that the dressing so produced is heat-resistant in a satisfactory degree and that the inflammability of the fibrous matter so treated is reduced. Moreover the British specification No. 285,942 shows that acetate silk may be rendered more absorptive for dyes by being treated with urea as a swelling means. From ancient times it is also known to use urea (urine) as a means for promoting the felting process of cloth and felt of any description.

It has been found that the molecular compounds of urea, its derivatives and products of substitution permit of securing particular dressing effects on account of their favorable properties. These molecular compounds are characterized by the general formula

in which M is a monovalent, divalent, trivalent or quadrivalent metal, e. g. sodium, magnesium, aluminium, zinc or cadmium, and X any anion. Some of these compounds may be mentioned here. So the "Journal für praktische Chemie" I, 35, 58 refers to the compound

the "Chemisches Zentralblatt" 1906, II, 1841 describes the compounds

35 and

40 the "Ann-a-len der Chemie" 101, 339 describe the compound

45 and a analogous cadmium chloride compound.

Almost all these molecular compounds are very soluble in water, highly hygroscopic and are even by the influence of the atmospheric humidity transformed from the crystalline condition into a syrupy form. On account of these properties they are particularly suited for being used as a dressing means and more generally for the treatment of textile goods. These compounds are also free from the inconvenience of being susceptible of separating out in a visible form on the fibres,

which is a well-known property of urea. Therefore they may be used in comparatively high concentrations without being perceived externally or covering the color. They impart fullness, gloss and weight to the fabrics treated therewith without impairing their natural character and moreover they show the advantage that on account of their neutral reaction they cannot adversely affect the color nor the fibres.

On account of these various favorable properties 65 the said molecular compounds distinguish themselves sensibly from the urea so that the use thereof in dressing and other treatments of fabrics is not only a novel process but also a substantial advantage.

In contrast to the British specification 285,942 the said compounds are used for an after-treatment and always after dyeing. The application may be done in the rinsing bath directly after the dyeing process or on a gumming or impregnating machine or on a reel or washing machine. It is also possible to pulverize the dressing solutions in order to be sprayed on the fabric, even for increasing weight only.

On account of the neutral reaction the combination with dressing means of any description is almost unlimited so that there is the possibility of producing socalled combination effects to a very wide extent which effects are often required for textile goods.

Example No. 1.—A viscose charmeuse is treated on the reel with a bath containing 5 kilos of carbamide-cadmium-chloride in 100 litres, and thereupon centrifuged and dried.

Example No. 2.—A pure-woollen gentleman's 90 cloth is passed on the padding machine through a bath containing 3 kilos of flake leather glue and 12 kilos of carbamide-sodium-chloride in 100 litres of water, thereupon squeezed, dried and hot-pressed.

Example No. 3.—On the reverse side of a coloured cotton fabric is sprayed a dressing solution containing 10 kilos of soluble starch and 15 kilos of carbamide-zinc-chloride in 100 litres of the liquid, thereupon dried and calendered.

The method is applicable to treating textile goods of any description made of silk, cotton, artificial silk or mixtures thereof.

I claim

1. A method for treating textile goods of any 105 description made of wool, cotton, artificial silk, or mixtures thereof, which comprises dyeing the goods and then treating the same with a neutral water-soluble hygroscopic molecular compound of a carbamide.

110

2. A method for treating textile goods of any description made of wool, cotton, artificial silk, or mixtures thereof, which includes the step of treating the same with a molecular compound of carbamide with a metal chloride, said molecular compound being water-soluble and hygroscopic. 80
 5 scopic molecular compound of a substance of the group consisting of carbamide and its substitution products and derivatives.
 3. A method for treating textile goods of any
